CHAIR FOR USE IN WASHING WINDOWS

Ettore F. B. De Meo, Brooklyn, N. Y.

Application June 27, 1950, Serial No. 170,506

3 Claims. (Cl. 155—131)

1

This invention relates to chairs and more particularly to a chair especially arranged to be mounted on a window ledge to support a person when washing the outer surface of a window.

It is among the objects of the invention to provide a chair which can be firmly mounted on a window ledge to provide a safe support for a person washing the outside of the associated window, which can be quickly and easily mounted in a window by merely hooking it over the window ledge, which includes safety features to prevent the chair from being dislodged even if the wood work of the window ledge should give way, which is light in weight so that it can be easily handled and provides a comfortable seat, which can be used as an ordinary chair when not in use for washing windows, and which is simple and durable in construction, economical to manufacture, and neat and attractive in appearance.

Other objects and advantages will become apparent from a consideration of the following description and the appended claims in conjunction with the accompanying drawings wherein:

Figure 1 is an elevational view of an inner side of a window with a chair, illustrative of the invention, mounted on the window ledge;

Figure 2 is a cross sectional view on the line 2—2 of Figure 1;

Figure 3 is a rear elevational view of the chair;

Figure 4 is a top plan view of the chair;

Figure 5 is a cross sectional view on the line 5—5 of Figure 3;

Figure 6 is a cross sectional view on the line 6—6 of Figure 5, looking in the directions of the arrows; and

Figure 7 is a perspective view of a hook assembly secured on the seat of the chair for engagement with the window ledge.

With continued reference to the drawings, the window opening is provided in a building wall 10 and the window has a frame including a window ledge, generally indicated at 11, and upper and lower sashes 12 and 13 slidably mounted in the frame. The ledge 11 includes an outwardly inclined sill 14 the outer edge of which projects outwardly beyond the outer side of the building wall at the bottom of the window opening, a stool 15 extending along the inner edge of the sill 14 and projecting inwardly of the inner side of the building wall and a trim strip 16 extending along the inner side of the wall at the lower side of the stool 15.

As window structures are old and well known to the art and, as the chair of the present invention may be used with various types of window

2

structures, a more detailed description of the window construction is considered unnecessary for the purposes of the present disclosure.

The chair comprises a rectangular seat 17 which may be formed of any suitable material, such as wood or metal, a back 18 extending at one edge along one edge of the seat and projecting substantially perpendicularly from one side of the seat, front legs 19 and 20 extending from the opposite side of the seat at the corners thereof remote from the back 18 and rear legs 21 and 22 projecting from the side of the seat opposite the back 18 and at the corners of the seat adjacent the back.

5 In the arrangement illustrated the front legs and the back are provided from a single piece of metal tubing which is first bent adjacent its mid-length location to a substantially U-shape, the intermediate portion 23 of which provides the 10 top of the back and the side portions or legs of which provide the side members 24 and 25 of the back. This U-shape structure is then provided with two substantially right angular bends which are opposite in direction and spaced apart so that 15 one of the bends occurs at the proximal ends of the back members 24 and 25 and the other occurs at the proximal ends of the front legs 19 and 20. This provides two rails 26 and 27 which are disposed substantially at right angles to the associated 20 back side members and front legs with the rail 26 connecting the proximal end of the front leg 19 to the proximal end of the back side member 24 and the rail 27 connecting the proximal end of the front leg 20 to the proximal end of the back side member 25. The seat 17 rests at 25 its opposite sides on the rails 26 and 27 and is firmly secured to these rails by suitable means, such as the clips 28 riveted or otherwise firmly secured to the under side of the seat and to the 30 rails.

35 Each of the rear legs 21 and 22 is separately provided and comprises a length of metal tubing bent to the form of a reversed "S". Each of the 40 rear legs has a portion extending along the corresponding rail and provided with an elongated slot, as indicated at 29 in Figure 5, and each rail is provided with an aperture registering with the slot. A bolt or other suitable fastener 30 extends 45 through the aperture in each rail and through the slot in the corresponding rear leg to adjustably connect the rear legs to the associated rails, the leg 21 being connected to the rail 26 and the leg 22 being connected to the rail 27, as is particularly illustrated in Figure 6.

50 A hook structure, generally designated at 31

and particularly illustrated in Figure 7, is rigidly secured to the under side of the seat 17 between the rails 26 and 27. This seat structure includes two lengths of suitable tubing, as designated at 32 and 33 disposed in spaced apart and substantially parallel relationship to each other. The member 32 has a straight shank portion 34 on one end of which is provided a curved hook formation 35 of substantially U-shape. The shank 34 is provided at spaced apart locations therealong with apertures 36 and 37 and is provided between these apertures with an elongated slot 38 which extends through the shank in a direction substantially perpendicular to that in which the apertures 36 and 37 extend therethrough.

The member 33 comprises a straight shank portion 40 and a U-shape hook formation 41 at one end of the shank portion. The shank portion 40 is provided with spaced apart apertures 42 and 43 and with an elongated slot 44 between the apertures and extending through the shank in a direction substantially perpendicular to that in which the apertures extend through the shank.

A bar 45 extends transversely of the shank portions 34 and 40 near the ends of the latter remote from the hooks 35 and 41 and is provided with transverse grooves disposed one near each end thereof which grooves respectively receive the slotted portions of the shanks 34 and 40. Screws 46 and 47 extend longitudinally of the bar from the respectively opposite ends thereof and extend through the slots in the corresponding shanks to adjustably secure the members 32 and 33 to the bar. The surface of the bar 45 remote from the seat 17 is bevelled to fit the outwardly sloped or inclined window sill 14.

The members 32 and 33 are rigidly secured to the under side of the seat 17 by suitable fasteners extending through the apertures 36, 37, 42 and 43 so that the shank portions of these members are substantially parallel to the rails 26 and 27, the member 32 being disposed adjacent the rail 26 and the member 33 adjacent the rail 27, and so that the hook formations 35 and 41 extend perpendicularly away from the seat with their open ends facing the rear legs of the chair.

With this arrangement, when the hook formations 35 and 41 are engaged over the inner edge of the window stool 15, as is particularly illustrated in Figure 2, the rails 26 and 27 extend across the window ledge assembly and the inwardly curved rear legs 21 and 22 bear near their lower ends, that is their ends remote from seat 17, against the outer side of the building wall below the window opening therein. This arrangement rigidly supports the chair on the window ledge so that a person may safely sit in the chair while washing the outer side of the window.

The rear legs may be adjusted inwardly and outwardly relative to the seat to condition the chair to the width of a particular window ledge and the bar 45 may be adjusted along the shank portions of the hook members 32 and 33 so that this bar will rest at the proper position on the upper surface of the sloped window sill.

In order to provide an additional factor of safety an elongated tubular arm 50 is pivotally connected at one end to the leg 19 adjacent the seat 17 by a hinge 51 the axis of which is substantially parallel to the front leg 19 and a similar arm 52 is connected to the front leg 20 by an associated hinge 53.

When the chair has been placed in the window opening, as illustrated in Figure 2, the front legs will be spaced inwardly from the trim strip 16

which extends along the inner side of the building wall below the window stool 15. The distal ends of the arms 50 and 52 may be brought into engagement with this trim strip to hold the chair against dislodgment in the event the wood work including the window stool 15 and the ledge 14 should give way under the weight of a person seated in the chair. As the trim strip is disposed directly against the building wall, the arms 50 and 52 will hold the chair against a serious displacement even though the window stool engaged by the hooks should be disrupted.

In the case of wide windows, the chair can be easily slid along the window ledge to render the entire outer surface of the window easily accessible and, if desired, suitable hooks or other attachments may be provided on the chair for supporting pails and other implements used in washing windows.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

I claim:

1. A chair for use in washing windows comprising a structure formed of a continuous length of metal tubing bent to provide a U-shaped back frame, a pair of front legs and side rails extending one between each front leg at the proximal end thereof and the corresponding side of said back frame at the open end of the latter, a seat mounted on said rails and secured thereto, rear legs secured one to each of said rails adjacent said back frame and extending from said rails in a direction away from said back frame, each of said rear legs being curved intermediate its length toward the corresponding front leg, means providing adjustable connections between said rear legs and said rails for movements of adjustment of said rear legs toward and away from the corresponding front legs, a pair of hook members each including an elongated straight shank and a hook formation at one end of said shank disposed against the under side of said seat between said rails with the shanks disposed one adjacent and substantially parallel to each rail and the hook formation disposed adjacent the edge of said seat remote from said back frame and extending perpendicularly away from the under surface of said seat to engage the inner edge of a window stool, means securing the shank of said hook members to said seat, and an abutment bar extending between the shanks of said hook members and adjustably connected at its ends to the latter for movements of adjustment longitudinally of said shanks.

2. A chair for use in washing windows comprising a structure providing a U-shaped back frame, a pair of front legs, and side rails disposed substantially perpendicularly to said front legs and said back frame and extending one between each front leg at the proximal end thereof and the corresponding side of said back frame at the open end of the latter, a seat mounted on said rails and secured thereto, rear legs secured one to each of said rails adjacent said back frame and extending from said rails in a direction away from said back frame, each of said rear legs being bent intermediate its length toward the cor-

responding front leg, means providing adjustable connections between said rear legs and said rails for movements of adjustment of said rear legs toward and away from the corresponding front legs, a pair of hook members each including an elongated straight shank and a hook formation at one end of said shank disposed against the under side of said seat between said rails with the shanks disposed one adjacent and substantially parallel to each rail and the hook formations disposed adjacent the edge of said seat remote from said back frame and extending perpendicularly away from the under surface of said seat to engage the inner edge of a window stool, means securing said shanks to said seat, and an abutment bar extending between the shanks of said hook members and adjustably connected at its ends to the latter for movements of adjustment longitudinally of said shanks, said bar having its surface remote from said seat beveled to fit up on a sloping window ledge.

3. A chair for use in washing windows comprising a structure formed of a continuous elongated member bent to provide a U-shaped back frame, a pair of front legs and side rails disposed substantially perpendicularly to said back frame and said front legs and extending one between each front leg at the proximal end thereof and the corresponding side of said back frame at the open end of the latter, a seat mounted on said rails and secured thereto, rear legs secured one to each of said rails adjacent said back frame and extending from said rails in a direction away from said back frame, each of said rear legs being curved intermediate its length toward the corresponding front leg, means providing adjustable connections between said rear legs and said rails for movements of adjustment of said rear legs toward and away from the corresponding front legs, a pair of hook members each including an elongated straight shank and a hook formation at one end of said shank disposed against the under side of said seat between said rails with the shanks disposed one adjacent and substantially parallel to each rail and the hook formations disposed adjacent the edge of said seat remote from said back frame and extending perpendicularly away from the under surface of said seat to engage the inner edge of a window stool, means securing said shanks to said seat, and an abutment bar extending between the shanks of said hook members and adjustably connected at its ends to the latter for movements of adjustment longitudinally of said shanks, said bar having its surface remote from said seat beveled to fit up on a sloping window ledge.

5 gated straight shank and a hook formation at one end of said shank disposed against the under side of said seat between said rails with the shanks disposed one adjacent and substantially parallel to each rail and the hook formations disposed adjacent the edge of said seat remote from said back frame and extending perpendicularly away from the under surface of said seat to engage the inner edge of a window stool, an abutment bar extending between the shanks of said hook members and adjustably connected at its ends to the latter for movements of adjustment longitudinally of said shanks, and arms pivotally connected one to each of said front legs adjacent said seat, each of said arms being connected at one end to the corresponding front leg for swinging movement about an axis substantially parallel to the longitudinal center line of the corresponding front leg to permit said arms to be wedged between said front legs and the inner side of a building wall at the bottom of a window opening and to provide an attachment in addition to said hook members for retaining the chair in position in a window opening.
